(57) **CLAIM**

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged detail of portion 8 shown in FIG. 1. The evenly spaced broken lines depict portions of the beverage container that form no part of the claimed design. The dot-dot-dash broken lines in FIGS. 1 and 8 depict partial view indicia and form no part of the claimed design.

1 Claim, 8 Drawing Sheets
